UNITED STATES PATENT OFFICE.

WILLIAM E. WOOD, OF WILMETTE, ILLINOIS.

MANUFACTURE OF CAST-IRON PIPE.

1,323,515.

Specification of Letters Patent.

Patented Dec. 2, 1919.

Application filed February 4, 1918. Serial No. 215,298.

To all whom it may concern:

Be it known that I, WILLIAM E. WOOD, a citizen of the United States, and resident of Wilmette, county of Cook, and State of Illinois, have invented certain new and useful Improvements in the Manufacture of Cast-Iron Pipe, of which the following is a specification, and which are illustrated in the accompanying drawings, forming a part 10 thereof.

The invention relates to an improved production of metal castings, particularly cast iron pipe, the principal objects being to secure greater uniformity in the quality of the 15 product and to promote economy in manufacture. To this end, a number of improvements in the methods and apparatus to be employed are contemplated, those forming the subject of this application being more 20 especially concerned with the use of a traveling mold support, moving in a circuit, and the use of molten metal principally supplied from smelting furnaces without cooling and remelting.

25 In the accompanying drawings wherein some of the features of well known construction are only conventionally represented;—

Figure 1 is a general ground plan showing 30 one arrangement of a foundry, with its associated buildings and tracks, which may be employed in practising the improved method or process provided by the invention;

Fig. 2 is a second floor plan of the foundry 35 illustrated in Fig. 1;

Fig. 3 is a sectional view, the sectional plane being indicated by the lines 3—3 on Figs. 1 and 2;

Fig. 4 is a detail plan view showing one 40 of the traveling mold supports illustrated in Figs. 1 and 2 with an associated crane;

Figs. 5, 6 and 7 are sectional views taken on the lines 5—5, 6—6 and 7—7 respectively of Fig. 4; Fig. 5 being a detail view drawn 45 upon an enlarged scale;

Figs. 8 and 9 are side and end elevations respectively of apparatus which may be employed for making the cores; and

Fig. 10 is a detail plan view of one of the 50 core strikes.

A convenient arrangement of the improved foundry is generally represented at 55 on Fig. 1. As shown, the foundry is equipped with a series of the traveling mold supports 26, 27, 28, 29, arranged to accom-

modate flasks, as 30 (Fig. 4) for pipe of the different but more usual sizes. Preferably the foundry is also equipped with stationary benches 31, for receiving the larger pipe flasks (not shown) and it includes, in addition, a separate floor 32 where the so-called "specials" may be molded and cast in the usual way. In accordance with the preferred plan, the foundry 25 is located immediately adjacent the blast furnaces, as 33, 34, and the complete plant further comprises a gas washer 35, power house 36, shop 37, for making and spooling the hay rope, storage sheds 38, 39, for the mold blacking and hay, and clean-out sheds 40, where the removal of the cores and other finishing operations may be performed, in any preferred manner.

As it is proposed to use metal from the blast furnaces, as 33, 34, without remelting, 75 the foundry 25 is preferably equipped with mixers, as 41. These are desirably located upon the ground floor, as 42, where they are served by a track 43 leading directly from the blast furnaces. The mixers 41 may be 80 of usual construction, each having capacity to retain sufficient molten metal for securing substantial uniformity by mixing together a plurality of separate tappings from the blast furnaces and occasional tappings from 85 cupolas, two of which are indicated at 44, as may be required from time to time for correcting the metal. The mixer metal is conveniently handled in a track 45, preferably arranged in a circuit to serve all of the 90 traveling mold supports, 26, 27, 28, 29, the benches 31 and the specials floor 32. To permit of the use of melted pig iron for the making of castings, as in the case of a temporary failure of the blast furnace metal, a 95 branch 110 of the track 45 extends in front of the cupolas 44.

The core ovens 46 are principally located upon the second floor, as 46 (Fig. 3) although the drawings indicate two additional sets of core ovens 48, 49, on the ground floor 42. These last mentioned sets of core ovens may be used exclusively for the so-called head cores (not shown) and one of the sets, as 49 serves only the larger flasks (not shown) on the benches 31. When this arrangement is employed, a set of mud mills 50 for mixing the core materials are also located on the ground floor 42. As shown, each two adjacent mud mills are 110

served by a separate jib crane 51, and the mixed core materials from all of the mills are handled on a track 52. The track 52 is conveniently also used for transporting such 5 other supplies as may be required both on the first and second floors 42, 47, of the main foundry 25 and on the specials floor 32. This track accordingly leads from the storage sheds 38, 39, and shop 37, through 10 the main part of the foundry 25 adjacent the mud mills 51 where it connects with each a plurality of hoists 53 delivering to the second floor 47, and it also connects with a part of the track 45 on the specials floor 32. 15 A branch 54 of the track 52 extends to the core ovens 48. On the second floor 47, a track 55 connects with each of the hoists 53 and extends throughout the length of the foundry, while branches 109 from this 20 track extend adjacent each of the traveling mold supports 26, 27, 28, 29, and the benches 31, all of which, though located on the first floor 42, are exposed through openings, as 99, 100, in the second floor. 25 The pipe cores are most conveniently made upon a movable platform, as 56, or 57 (Fig. 2), hereinafter referred to as the core car. As shown, two of these core cars are provided and both move upon a track 58. 30 This track extends immediately in front of the core ovens 46, adjacent to and parallel with track 55. The core cars, as 56, 57, are thereby conveniently supplied with the spooled hay rope and other core making materials delivered to the second floor 47 by the hoists 53, in any position of the cars along the track 58.

The core car 56 is illustrated in detail in Figs. 8 and 9. As this core car is more particularly intended for making cores for the medium and smaller sizes of pipe it is equipped with two core strikes 59, 60, one adjacent each end of the car. It is also equipped with two sets of mud boxes 61, 40 one for serving each of the core strikes 59, 60. The core car 57 may be of the same construction as the core car 56 but it is preferably provided with a single core strike 62 of large size and with a single 45 set of mud boxes 63.

For convenience in handling the trucks, as 64, (Fig. 8) upon which the cores are baked, the core car 56 carries a transverse track 65 upon which one of these trucks may 50 be held. The core car 57 is equipped with a similar track 107 of wider gage for receiving a larger truck (not shown). In the case of the car 56, the transverse track 65 is located centrally between the two core 55 strikes 59, 60. Each truck 64 is equipped with racks 66 for containing a plurality of cores, as 67, of a given size, and the truck 64 stands upon the corresponding track 65 while a quantity of the cores contained in the rack 65 60 are successively transferred to the adja-

cent core strike 59, 60, for manipulation therein.

For convenience in handling the cores, as 67, in transferring them to the core strikes 59, 60 or 62 and returning them to the rack 70 66 each of the core cars 56, 57, is preferably equipped with an over-head hoist 70. As shown, this over-head hoist is provided with wheels 71 at each side and these wheels run upon elevated rails 72 carried by the 75 corresponding car, as 56. The hoist may thus be moved from end to end of the car. The hoist 70 also comprises a pair of connected winding drums 73, one at each side, and two hoisting chains 74, one wound upon 80 each of the drums 73. Each chain 74 terminates in a hook 75 adapted to be entered in one end of the usual foraminous tubular core bar, as 76, upon which each of the cores, as 67, is formed. The construction 85 of the core car, as 56, is not specifically claimed herein for the reason that it forms the subject of my copending application for patent on core making apparatus.

When the cores contained in a truck 90 rack 66 are ready for baking, the core car, as 56, carrying the corresponding truck 64 is moved on the track 58 to a position directly in front of one of the ovens 46 and the truck 64 is transferred from the car into 95 the oven, as upon track 108 provided for that purpose. To permit all of the sizes of pipe cores to be baked in any of the ovens 46, each of these ovens is preferably equipped with two of the tracks 108. Two 100 of the trucks 64 may accordingly be entered side by side upon the two tracks 108 in each oven, or the larger truck (not shown) used on the core car 57, spans both of these tracks. When the cores are to be 105 withdrawn from the oven, one of the cars 56, 57, is again positioned in front of the oven for receiving the truck 64 on its track 65 or 107. In case the corresponding cores have been previously supplied with both the 110 first and second coats, the car 56 or 57 is now used for carrying the truck 64 to a position where it may be transferred to one of a series of stationary tracks 68 or 69, upon which the truck stands during the removal of the finished cores therefrom. 115

While cores for pipe of the smaller sizes are readily unloaded from the truck, as 64, by hand, the handling of some of the cores, as also the delivery of core making material 120 onto the core cars 56, 57, is more conveniently performed if an over-head traveling crane, as 77, is provided. As shown, this crane runs throughout the length of the main part of the foundry 25 and is of sufficient, 125 length to extend entirely over the tracks 55, 58, the hoist 53 and also for some distance over the unloading tracks 68, 69.

Except in the making of pipe of the very largest sizes the operations of baking the 130

molds, setting the cores therein and pouring the castings, are preferably all performed while the corresponding flasks, as 30, are carried by one of the traveling mold supports 26, 27, 28, 29. In the making of large pipe, the corresponding operations are performed while the flasks (not shown) are mounted on the benches 31. The traveling mold supports 26, 27, 28, 29, may be of like 5 construction, except that they are differently proportioned for supporting flasks of different sizes. For this reason only one of these supports, as 27, is illustrated in detail.

As most clearly shown in Figs. 4, 6 and 7, 10 the traveling mold support 27 principally comprises an annular frame 78 and this frame completely encircles a central stationary pier 79. A simple and convenient means of carrying the flasks is provided in 15 the form of a continuous shelf 80 which projects outwardly from the lower edge of the frame 78 and the flasks, as 30, (Figs. 3, 4, and 5) stand upon this shelf, preferably with the molds, as 90, 91, contained therein, registering 20 with apertures 89, 89^a, formed in the shelf. If the parts are so proportioned that the frame 78 and pier 79 reach to the level of the second floor 47, while the upper ends 25 of the flasks 30, when standing on the shelf 80, project somewhat above this level, the flasks are rendered accessible for setting the cores, gating and pouring in the same manner as if held in a pit, except that during all 30 of these operations the flasks partake of the movement of the frame 78.

For supporting the frame 78 a circular track 81 is provided. As shown, this track extends under the frame and truck wheels 82, mounted against the under side of the 35 frame, run on the track. As it is proposed that all of the operations incident to the production of cast iron pipe shall proceed continuously, the frame 78 preferably revolves continuously but at such a rate that the baking of the molds, the setting of the 40 cores, the gating, pouring and cooling of the castings may be accomplished during one revolution.

The driving of the frame 78 is conveniently accomplished by chambering the pier 45 79 and mounting a motor 83 and speed reducing gears 84 within the chamber of the pier. As shown, the speed reducing gears 84 drive the two ends of a sectional shaft 85 in opposite directions and this shaft extends 50 horizontally through the pier and is equipped at its opposite ends with oppositely turning pinions 86, 87, which mesh with an annular gear rack 88 carried by the 55 frame 78.

The baking of the pipe molds may be accomplished by any desired form of heater adapted to admit heat to the molds, as 90, 91, through the apertures 89, 89^a, of the shelf 60 65 80 during a substantial part of the revolution

of the frame 78. The heater shown in the drawings comprises a plurality of stationary gas burners 92 located below the shelf 80 at one side of the pier 79 and arranged in curved rows conforming to the paths of movement of the apertures 89 and 89^a. When this form of heater is employed, provision is preferably made for checking the flame from each burner 92 except when one of the apertures 89 or 89^a is passing over 70 the same during the revolution of the frame 78. As shown, each burner 92 is equipped with a rotating gas valve 93 and a series of contact arms 94 depend from the shelf 80 for rotating the valve 93 of each burner by 75 contact with the corresponding valve stem. If the contact arms 94 are spaced along the shelf 80 in accordance with the spacing of the flasks, as 30, on the shelf, each gas valve 93 will be alternately opened and closed for 80 directing a flame from the corresponding burner 92 into the molds 90 or 91, as the apertures 89 or 89^a pass over the burner during the revolution of the frame 78, and for 85 checking the flame from the burner when it would otherwise merely impinge the underside of the shelf between adjacent apertures 89 or 89^a.

The particular arrangement of parts illustrated in the drawings contemplates that the 90 molding will be accomplished in each of the flasks 30 while it is removed from the corresponding mold support, as 27. For this purpose a molding machine 95 is associated with each traveling mold support, 26, 27, 28, 29, 100 being preferably located at that side of the same which is adjacent the clean-out sheds 40. Under these circumstances a crane 96 (Fig. 3) serves for removing the flasks 30 from each traveling mold support, as 27, 105 shaking out the castings, depositing the empty flasks on the corresponding molding machine 95 and returning the flasks with new molds, as 90, 91, formed therein, to the traveling mold support. 110

As the flasks 30 may be of well known construction, the castings may be shaken out and the new molds produced in accordance with the usual practice. As shown, a set of skids 97 (Figs. 2 and 3) upon which 115 the castings are deposited by the shake out, extend into the clean-out sheds 40 from a point adjacent each of the traveling mold supports 26, 27, 28, 29, within the range of the corresponding crane 96. If desired a conveyer 98 may extend under all of the skids 97 for collecting the molding sand which falls from the flasks during the shake out. It will be understood that each flask 30 remains upon one of the traveling mold 120 supports, as 27, throughout nearly a complete revolution of the same and that it is only removed as it approaches the corresponding skids 97, its place upon the traveling support being immediately thereafter 125 130

filled with a previously removed flask which has been supplied with new molds while on the adjacent molding bench 95.

While the setting of the cores, as 67, and 5 the pouring of the castings will usually be accomplished in each flask 30 during its travel through a relatively short range, preferably at the remote side of the corresponding pier 79 from the shake out crane 10 96, a movable crane generally designated 101, is desirably mounted upon each pier for serving any part of the associated traveling mold support 26, 27, 28, or 29, as also any 15 part of the top of the pier and adjacent parts of the second floor 47. For the purpose of illustrating the present invention, the crane 101 is shown as having the form 20 of a revolving gauntletree, turning on a circular track 102. The track 102 is mounted on the pier 79 while the crane girders 103 extend diametrically over the pier and for a substantial distance beyond the same at each 25 end. The turning of the crane upon the track 102 thereby enables the hoist 104, running on the girders 103, to command any part of the top of the pier 79 and a considerable area beyond the same in any direction.

To facilitate the transfer of large objects, 30 as for example, a ladle of hot metal (not shown), directly from one side of the pier 79 to the other, the columns, as 105, which support the crane girders 103, slope outwardly to provide a wide space between 35 them through which a ladle or the like may be carried. As this method of operating the crane will not permit of the use of bracing between the corresponding columns 105 supporting the two girders 103, except near 40 the lower ends of the columns, the framework of the crane is braced by connecting these columns at their upper ends with yokes 106 which arch over the girders 103. At their lower ends, the columns 105 are 45 equipped with flanged wheels 111 which run upon the circular track 102.

Although the movement of each traveling mold support, as 27, is quite slow, it is believed to be desirable that this movement 50 should not be interrupted at any time. The lowering of the cores, as 67 (Fig. 3) into the molds and the pouring of the castings are accordingly to proceed with the flasks 30 in motion. As each of these operations is preferably, accomplished with the use of the hoist 104 of the gauntletree crane 103, provision is advisably made for causing the crane 55 to partake of the movement of the corresponding traveling mold support, as 27, as 60 by coupling the crane to the revolving frame 78. For this purpose, the revolving frame 78 may be provided with a continuous upstanding flange 112 (Fig. 6) and the frame of the crane 101 is supplied with two 65 oppositely positioned sets of clamping jaws

113, 114, arranged to frictionally grip the flange 112 between them in any relative position of the crane and rotating frame 78.

As shown, the supporting columns 105 of the gauntletree crane 101 are connected near 70 their lower ends by a circular frame 115, and a platform 116 extends over this frame. Each of the clamping jaws 113, 114 is formed with an instanding arm 117 and the arms 117 of the two jaws of each set are 75 slidingly secured against the under side of the frame 115. When this form of construction is employed, a foot pedal 118, reaching through the platform 116 may be employed for compressing the clamping jaws 113, 114, 80 of both sets upon the flange 112. To this end, a bell crank lever 119 is pivotally connected with the arm 117 of one of the jaws 113 and one arm of this lever is connected with the stem of the foot pedal 118 while 85 the other arm of the lever bears against the end of the arm 117 of the companion jaw 114. The jaws 113, 114, of the other set are operated by a lever 120 and a link 121 connecting this lever with the bell crank lever 90 119. The lever 120 is pivotally mounted upon the arm 117 of the corresponding jaw 113 and bears against the inner end of the arm 117 of the companion jaw 114.

Movement of the gauntletree crane 101 95 upon the circular track 102, otherwise than by coupling the crane to the revolving frame 78, is preferably accomplished by driving the wheels 111 with an electric motor 122. For convenience in operating the crane the 100 controller 123 for the motor 122 may be located on the platform 116 adjacent the foot pedal 118. The conductors, as 124, for supplying current to the motor 122, pass through a central opening 125 in the top of 105 the pier 79, where a swiveled connector 126 is provided to accommodate the conductors to the revolution of the crane upon the circular track 102. Should it be desired to lock the crane against angular movement in 110 any position, a circular upright stationary flange 127, similar to the flange 112 on the revolving frame 78, may be mounted on the pier 79. When such a flange is provided, the crane 101 is desirably equipped with additional clamping jaws 128, 129, similar to the clamping jaws 113, 114, and adapted to be operated by a foot pedal 130 for gripping the flange 127 in exactly the same manner that the jaws 113, 114 are operated by 115 the foot pedal 118 for gripping the flange 112.

For setting the pipe cores in the molds, as 90, 91, contained in a flask 30, the crane attendant standing on the platform 116, by 120 operating the crane to travel on the circular track 102, brings the hoist 104 over the cores lying on the second floor 47 where they have been unloaded from a truck 64 standing on one of the tracks 68. After lifting a pair of 125 130

the cores 67 from the floor, as in Fig. 3, the crane is again operated to travel on the circular track 102 until the hoist is brought into radial alinement with the particular 5 flask 30 in which the cores are to be deposited. By depressing the foot pedal 118 the crane is now coupled with the revolving frame 78 and, by adjusting the hoist 104, the cores are lowered into the flask as readily 10 as if both the flask and crane were stationary. Similarly, for pouring the castings, the ladle (not shown) is held in the hoist 104 and the crane is coupled to the revolving frame 78 when the hoist has been brought 15 to a suitable position with respect to the flask to be poured. As the mixers 41 and hot metal track 45 are located on the ground floor 42, the ladles (not shown) are elevated by the hoists 104, and deposited when empty, 20 through openings 131 in the second floor 47, one of which is provided adjacent each of the traveling mold supports, as 26, 27, 28, 29. For these operations the corresponding crane, as 101, may be held against movement on the circular track 102 by depressing 25 the foot pedal 130.

While it is proposed to employ the same crane 101 for performing the two operations of setting the cores and pouring the castings upon each of the traveling mold supports, as 26, 27, 28, 29, whereby these operations may not proceed at the same time, each 30 operation is as nearly continuous as is required to afford a regular delivery of castings from each traveling mold support to the corresponding skids 97. Furthermore, the use of the core car, as 56, and mixers 44 provide a continuous supply of cores and hot metal.

40 It will be understood that the angular position of the flasks about the pier 79, during the pouring of the castings is separated a sufficient distance from the position of the same flasks during the setting of the 45 pipe cores, to provide an interval for the fitting of the head cores (not shown), in the usual way, during the travel of the mold support. On the other hand, the angular position of the flasks about the pier 79, during 50 the pouring of the castings, is sufficiently removed from the corresponding skids 97, to provide a substantial interval for the cooling of the castings in each flask during the travel of the mold support, before the flask 55 reaches the position where it is removed from the shelf 80 by the shake-out crane 96. The benches 31 are served by a traveling crane 133 through the opening 100 in the floor 47, the crane-way 132 extending out through the 60 side of the building over the corresponding skids (not shown).

I claim as my invention:

1. In a foundry plant, the combination with a blast furnace and a mixer for containing 65 a plurality of separate tappings from

the blast furnace, of a traveling mold supporting frame moving in a circuit, molds carried by the frame, metal pouring apparatus movable with the mold frame throughout a part of its travel in the said circuit and 70 means directly supplying the metal pouring apparatus from the mixer.

2. In a foundry plant, the combination with a blast furnace and a mixer for containing a plurality of separate tappings 75 from the blast furnace, of a traveling mold supporting frame moving in a circuit, a plurality of independent tubular upright molds removably supported on the said frame, a heater below the mold supporting frame and 80 registering with the bores of the said tubular molds supported thereon throughout a part of the travel of the mold frame, and metal pouring apparatus supplied from the mixer and movable with the mold frame throughout a 85 different part of its travel in the said circuit.

3. The method of manufacturing cast iron pipe and the like which consists in mixing a plurality of separate tappings of blast furnace metal while in their original molten 90 state, moving a series of pipe molds in a circuit, and baking the molds, setting cores therein and pouring the molds from the mixed blast furnace tappings without remelting during different parts of the travel 95 of the molds in the said circuit.

4. The method of manufacturing cast iron pipe and the like which consists in mixing a plurality of separate tappings of blast furnace metal while in their original 100 molten state, maintaining a continuous travel of a series of pipe molds in a circuit, and baking the molds, setting cores therein and pouring the molds from the mixed blast furnace tappings without remelting, all of 105 the last three mentioned operations being performed in substantially continuous succession upon adjacent molds in the series while traveling through different parts of the said circuit.

5. The method of manufacturing cast iron pipe and the like which consists in maintaining a continuous travel of a series of pipe molds in a circuit, and baking the molds, setting cores therein and pouring the 115 molds with molten metal, all of the last three mentioned operations being performed in substantially continuous succession upon adjacent molds in the series while traveling through different parts of the said 120 circuit.

6. The method of manufacturing cast iron pipe and the like which consists in mixing a plurality of separate tappings of blast furnace metal while in their original 125 molten state, maintaining a continuous supply of molds for the articles to be cast by moving a series of the mold flasks in a circuit and pouring adjacent molds in the series from the mixed blast furnace tap- 130

pings without remelting in substantially continuous succession during their location in a given part of the said circuit of travel.

7. The method of preparing pipe molds 5 and the like for casting which consists in maintaining a continuous travel of a series of mold flasks in a circuit and baking the molds and setting cores therein while the mold flasks are in motion during their 10 travel through different parts of the said circuit.

8. The method of manufacturing cast iron pipe and the like which consists in mixing a plurality of separate tappings of 15 blast furnace metal while in their original molten state, maintaining a continuous travel of a series of pipe molds in a circuit, and baking the molds, setting cores therein, and pouring the molds from the mixed blast 20 furnace tappings without remelting, all of the last three mentioned operations being performed in substantially continuous succession upon adjacent molds in the series while the said molds are in motion during 25 their travel through different parts of the said circuit.

9. The method of manufacturing cast iron pipe and the like which consists in maintaining a continuous travel of a series 30 of mold flasks in a circuit, baking the molds, setting cores therein and pouring the molds with molten metal, the last three mentioned operations being performed in substantially continuous succession upon adjacent molds 35 in the series while the said molds are in motion during their travel through different parts of the said circuit.

10. The method of manufacturing cast iron pipe and the like which consists in 40 maintaining a continuous travel of a series of pipe molds in a circuit, and baking the molds, setting cores therein and pouring the molds with molten metal, all of the last three mentioned operations being performed 45 in substantially continuous succession upon adjacent molds in the series while the said molds are in motion during their travel through different parts of the said circuit, and the parts of the circuit where pouring 50 and baking are accomplished being separated a substantial distance in the direction of travel of the molds to permit the cooling of the castings during the travel of the molds between said parts.

55 11. The method of manufacturing cast iron pipe and the like which consists in mixing a plurality of separate tappings of blast furnace metal while in their original molten state, maintaining a continuous 60 travel of a series of pipe molds in a circuit, and baking the molds, setting cores therein, and pouring the molds from the mixed blast furnace tappings without remelting, all of the last three mentioned operations being 65 performed in substantially continuous suc-

cession upon adjacent molds in the series while the said molds are in motion during their travel through different parts of the said circuit, and the parts of the circuit where pouring and baking are accomplished 70 being separated a substantial distance in the direction of travel of the molds to permit the cooling of the castings during the travel of the molds between said parts.

12. In a foundry plant, in combination, a 75 revolving frame constructed to removably support a series of separate mold flasks circumferentially arranged upon the frame, a molding platform located a one side of the frame, means for transferring the mold flasks between the frame and platform, and metal pouring apparatus movable with the frame.

13. In a foundry plant, in combination, a traveling frame constructed to removably 85 support a series of separate mold flasks, a ladle hoist movable in a path conforming to the path of movement of the frame, and means for coupling the ladle hoist to the frame.

90 14. In a foundry plant, in combination, a traveling frame constructed to removably support a series of separate mold flasks, a ladle hoist movable in a path conforming to the path of movement of the frame, means 95 for moving the ladle hoist in said path independently of the frame, and means for coupling the ladle hoist to the frame.

15. In a foundry plant, the combination with an elevated floor having an opening, 100 an annular revolving frame supported below the said floor and extending to the floor level at the said opening, a pier supported below the said floor within the annular frame and also extending to the floor level, 105 a series of upright mold flasks circumferentially arranged upon the revolving frame and supported thereby, and a crane mounted on the said pier constructed to command the said mold flasks throughout the entire 110 circumference of the revolving frame and an adjacent part of the said floor.

16. In a foundry plant, the combination with an elevated floor having an opening, 115 an annular revolving frame supported below the said floor and extending to the floor level at the said opening, a pier supported below the said floor within the annular frame and also extending to the floor level, 120 and a series of upright mold flasks circumferentially arranged upon the revolving frame and supported thereby to project above the floor level, the said pier, revolving frame and flasks substantially filling the floor opening.

125 17. In a foundry plant, in combination, a horizontally disposed annular revolving frame constructed to removably support a series of separate mold flasks, a pier rising within the revolving frame and substan- 130

tially filling the frame opening, a movable crane mounted on the pier constructed to command the mold flasks carried by the frame and an adjacent area beyond the frame, and means for coupling the crane to the frame.

18. In a foundry plant, in combination, a horizontally disposed annular revolving frame constructed to removably support a series of separate mold flasks, a pier rising within the revolving frame and substantially filling the frame opening, a movable crane mounted on the pier constructed to command the mold flasks carried by the frame and an adjacent area beyond the frame, and means for moving the crane independently of the frame.

19. In a foundry plant, in combination, a horizontally disposed annular revolving frame constructed to removably support a series of separate mold flasks, a swinging crane pivotally supported with the frame to command the mold flasks carried by the frame and an adjacent area beyond the frame, and means for coupling the crane to the frame.

20. In a foundry plant, in combination, a horizontally disposed annular revolving frame constructed to removably support a series of separate mold flasks, a swinging crane pivotally supported with the frame to command the mold flasks carried by the frame and an adjacent area beyond the frame, and means for swinging the crane independently of the frame.

21. In a foundry plant, the combination with an elevated floor having an opening, core making apparatus mounted on the said floor, an annular revolving frame supported below the said floor and extending to the floor level at the said opening, a pier supported below the said floor within the annular frame and also extending to the floor level, a series of upright mold flasks circumferentially arranged upon the revolving frame and supported thereby, and a crane mounted on the said pier constructed to command the said mold flasks throughout the entire circumference of the revolving frame and an adjacent part of the said floor.

22. In a foundry plant, the combination with an elevated floor having openings, core making apparatus delivering upon the said floor adjacent an opening therein, an annular revolving frame supported below the said floor and extending to the floor level at the last mentioned opening, a pier within the annular frame also extending to the said floor level, a series of upright mold flasks circumferentially arranged upon the revolv-

ing frame and supported thereby, the said pier, revolving frame and flasks substantially filling the last mentioned floor opening, and a swinging crane mounted on the pier to command the said mold flasks and an adjacent part of the said floor including space below the floor through another of its said openings.

23. In a foundry plant, the combination with an elevated floor having openings, core making apparatus delivering upon the said floor adjacent an opening therein, an annular revolving frame supported below the said floor and extending to the floor level at the last mentioned opening, a pier within the annular frame also extending to the said floor level, a series of upright mold flasks circumferentially arranged upon the revolving frame and supported thereby, the said pier, revolving frame and flasks substantially filling the last mentioned floor opening, a swinging crane mounted on the pier to command the said mold flasks and an adjacent part of the said floor including space below the floor through another of its said openings, and means for coupling the crane to the frame.

24. In a foundry plant, the combination with an elevated floor having openings, core making apparatus delivering upon the said floor adjacent an opening therein, an annular revolving frame supported below the said floor and extending to the floor level at the last mentioned opening, a pier within the annular frame also extending to the said floor level, a series of upright mold flasks circumferentially arranged upon the revolving frame and supported thereby, the said pier, revolving frame and flasks substantially filling the last mentioned floor opening, a swinging crane mounted on the pier to command the said mold flasks and an adjacent part of the said floor including space below the floor through another of its said openings, means for swinging the crane independently of the frame, and means for coupling the crane to the frame.

25. In a foundry plant, in combination, means for maintaining a continuous travel of a series of mold flasks through a circuit, means for baking and pouring the molds formed in the flasks during different parts of their travel through the circuit and continuously operable core making apparatus delivering the flasks at a place in their travel through the said circuit intermediate the places of operation of the baking and pouring means.

WILLIAM E. WOOD.
